SADAYOSHI NAKAHARA, OF NEW YORK, N. Y.

CLIP FOR FOUNTAIN PENS OR THE LIKE

Application filed September 29, 1930. Serial No. 485,149.

This improvement relates more particularly to an improved clip for fountain pens, mechanical pencils and the like, wherein a ball clip is provided for holding the pen or pencil attached to the pocket or to some other part of the clothing.

Clips of this character for fountain pens or the like are usually secured to the barrel or barrel cap by means of rivets or other 10 similar means, which are more or less unsightly and the clips cannot be readily attached or replaced.

The object of the present improvement is to provide novel means of attaching the clip 15 whereby the attaching means is concealed, thus producing a neat appearing article.

A further object is to provide simple means for attaching the clip, preferably consisting of a screw-threaded member on the end of 20 the barrel, cooperating with an annular flange or groove for holding the clip in fixed relation to the barrel and the end of the clip in cooperative relation with the screw-threaded member, that is the clip is adapted to be 25 held in place by the flange and the clamping effect of the screw-threaded member. This construction not only provides an efficient means for securing the clip to the pen or pencil, but provides a ready means permitting 30 the clip to be replaced if it becomes broken or damaged or if it otherwise becomes necessary to replace the clip.

The preferred form of the improvement 35 is more particularly shown in the accompanying drawings, in which Fig. 1 is a side view of the clip attached to a fountain pen barrel cap; Fig. 2 is a front view of the clip and cap as shown in Fig. 1; Fig. 3 is another 40 side view of the clip and barrel cap with the barrel and cap nut and the upper portion of the clip in section; Fig. 4 is a perspective view of the disassembled parts of the clip, barrel and cap nut; Fig. 5 is an end view 45 of the barrel and clip with the cap nut re-

moved and Fig. 6 is a bottom or underside view of the cap nut.

Referring to the drawings, it will be seen that the improvement is shown in connection with a fountain pen barrel or barrel cap A, although it will be understood that the clip attaching means may be employed in connection with magazine or mechanical pencils and the like.

As will be seen more particularly in Figs. 55 3, 4 and 5, the upper end of the barrel A is turned down in a radial plane to form a flat end surface B and, projecting from the center of this surface or axially of the barrel there is a screw-threaded stud C. A cap 60 nut D preferably knurled and of the same diameter as the end of the barrel, is provided with a central screw-threaded opening E for cooperation with the screw-threaded stud C. In the present instance, the underside 65 of the cap nut D is formed with a circular recess F producing an annular cylindrical flange G extending about the lower face of the nut, as indicated in Figs. 4 and 6. An arc-portion at H of the flange is cut away, 70 the ends of the flange at the cut-out portion being preferably in radial planes, as indicated at K.

The clip L may be punched out of sheet metal in the usual way and provided at its 75 lower end with the usual ball M, which may be integral or otherwise, as desired. The upper end of the clip is bent at N, substantially at right angles to the part L, and is punched or formed with a semi-circular arcuate portion O, adapted to fit in the recess F of the cap nut, adjacent the flange G. The portion O is preferably provided with a hole or cut-out portion at P, which is adapted to cooperate with the screw stud C and fit closely 85 thereabout, while the semi-circular outer edge of the portion O is adapted to fit closely in the recess F against the flange G.

Also, it will be seen, particularly from Fig. 5, that the bent-over portion of the clip be- 90

tween the bend N and the semi-circular portion O is formed wedge-shaped with its edges at R in radial planes corresponding with the radial planes or edges K (Fig. 6) of the annular flange G on the cap nut D.

Accordingly the clip is provided with a portion extending transversely of the end of the barrel and is secured thereto by the screw-threaded member, the clip being held in place 10 by the annular flange or screw-threaded stud, and in fixed position by the radially cut-out portion.

From the above, it will be understood that for attaching or removing the clip, the procedure is comparatively simple. For attaching the clip, the upper end of the clip O, P, R is inserted in the recess F with edges R in contact with the walls K of the cut out portion H, after which the cap nut D is screwed 20 down on the screw-threaded stud C, thereby clamping the upper transverse end of the clip to the end of the barrel between the flange G and the screw-threaded stud C, substantially as shown in Figs. 1, 2 and 3. When it is desired to remove the clip, the cap nut D is unscrewed enough to release the clip after which it may be readily removed and replaced with another clip or left off entirely if no clip is needed.

30 While the flange G and recess F are shown on the cap nut, it will be understood as a mere reversal to place them on the upper end of the barrel and while the opening in the flange is provided with wedge-shaped or radial edges for providing a wedging effect in holding the clip in position, this opening may have parallel edges or be formed otherwise if desired.

Furthermore, it will be understood that 40 various modifications in the details of construction and arrangement of parts may be made without departing from the spirit and scope of the invention.

I claim:—

45 1. In a fountain pen or the like, the combination with the barrel of a clip provided with a lateral portion extending transversely of the end of the barrel, said lateral portion having an arcuate portion, a screw-threaded stud with which said arcuate portion is adapted to cooperate and a cap nut on said threaded stud for securing the clip to the end of the barrel by means of said arcuate portion and means for retaining the clip in fixed relation to the barrel when secured by said cap nut.

50 2. In a fountain pen or the like, the combination with the barrel, of a screw-threaded member on the end of the barrel, a clip with a lateral portion adapted to extend transversely of the end of the barrel for securing the clip to the barrel by said screw-threaded member and an annular flange on the screw-threaded member 55 cooperating with said lateral por-

tion for retaining the clip in fixed relation to the barrel.

3. In a fountain pen or the like, the combination with the barrel, of a screw-threaded stud extending axially from the end of the barrel, a cap nut cooperating with said threaded stud, an annular flange on said cap nut, said flange being provided with a radial opening and a clip provided with a lateral portion adapted to extend through said radial opening and formed with an arcuate portion cooperating with said threaded stud for securing the clip to the barrel when the cap nut is screwed down.
